UNITED STATES PATENT OFFICE.

JOHN C. SPENCER, OF SPICELAND, INDIANA.

AUTOMATIC SHADE-ROLLER-CONTROLLING MEANS.

Application filed November 16, 1921. Serial No. 515,582.

To all whom it may concern:

Be it known that I, JOHN C. SPENCER, a citizen of the United States, residing at Spiceland, in the county of Henry and State of Indiana, have invented certain new and useful Improvements in Automatic Shade-Roller-Controlling Means, of which the following is a specification, reference being had to the accompanying drawings.

10 This invention relates to window shade fixtures, and more particularly to automatic means for controlling the movement of a spring actuated shade roller.

It is an object of the invention to provide means of this character capable of causing rotation of the shade roller upon actuation of the supporting means of the roller.

It is another object of the invention to provide means of this character wherein the rod on which the spring actuated shade roller is rotatably mounted also serves as the actuating member to release the roller with respect to its mounting and permit the spring of the roller to rotate the roller, the rotation of the roller being immediately stopped upon release of the actuating member through the medium of the spring of the roller.

It is also an object of the invention to provide means of this character embodying an actuating member substantially corresponding in length to the length of the shade roller and having shade brackets extending therefrom, the roller being rotatably mounted in the brackets, and gravity actuated means carried by one of said brackets and adapted to engage the roller to normally prevent rotation of the roller and to disengage and permit rotation of the roller when the actuating member is moved away from the shade of the roller by the operator.

It is a further object of the invention to provide means of this character including an actuating member on which a spring actuated shade roller is rotatably mounted, the actuating member and roller being movable in unison upon adjustment of the curtain by the curtain cord and movable independently of each other when the curtain cord is substantially locked in its adjusted position.

With these and other objects in view, the invention consists in the improved construction and arrangement of parts to be hereinin-

after more particularly described, fully 55 claimed and illustrated in the accompanying drawings, in which:—

Figure 1 is a view in elevation of a window shade showing the automatic shade controlling means applied; 60

Figure 2 is a side elevation of the structure shown in Figure 1;

Figure 3 is a plan and sectional view of the controlling means, the shade being removed; 65

Figure 4 is a section taken on the line 4—4 of Figure 3; and

Figure 5 is a detailed view of the drum or collar adapted to be engaged by the gravity pawl.

Referring to the drawings, 5 designates a window casing to the upper intermediate portion of which a lock pulley bracket 6 is secured. A lock pulley of conventional form is mounted in the bracket. The pulley is adapted to receive a curtain or shade cord 7 which is connected to the window shade 8. In order to permit the window shade to be properly balanced and maintained at all times in a horizontal position, there is provided a novel reinforcing bar 9 substantially 75 rectangular in cross section, said bar being disposed in a pocket 10 formed at one end of the shade. A balance cord 11 is secured at its ends to the reinforcing bar 9 through the medium of suitable fastening means and clips 12 to substantially provide a bail. One end of the cord 7 is provided with a loop 13 adapted to receive the cord 11, the loop being frictionally engaged with the cord 11 80 so that it will not move accidentally. By this means the operator can move the cord 7 relative to the cord 11 to properly position the shade. With the use of the cord 7 the entire shade and its roller may move longitudinally of the window casing to the point desired, whereupon the cord may be moved to one side to lock the same within the pulley.

In order to permit the length of the shade to be increased or decreased independently of the adjustment by the cord 7 there is provided a novel mechanism embodying an actuating bar 14 substantially corresponding in length to the length of the shade roller. Secured to 100 each end portion of the bar and projecting at right angles thereto are brackets 15 and 15^a. Rotatably mounted in the brackets is a shade

roller 16 having the usual actuating spring 17 disposed in one end thereof, said end including a stub shaft or pintle having a flat end portion 18 adapted to extend through a rectangular slot 19 provided in the bracket 15. The opposite end portion of the roller 16 is intended to receive a stub shaft 20, the end portion 21 of said shaft being flat and provided with an opening 22, while disposed 10 between the intermediate portion of the shaft and the opposite end portion 23 is a collar 24, said collar having a plurality of spaced openings or recesses 25. The end portion 21 of the stub shaft 20 is adapted 15 to be inserted in the last mentioned end of the shade roller, suitable fastening means being passed through the roller and the shade 22 to prevent movement of the stub shaft independently of the roller. The end portion 23 of the stub shaft is round and 20 adapted to be journaled in an opening 26 provided in the bracket 15.

To control rotation of the spring actuated shade roller, there is provided a housing 27, 25 said housing being formed from a sheet of material having its end portion 28 coiled upon said sheet to provide the housing 27. The opposite end portion 29 is provided with openings for the reception of rivets. 30 A stop or end wall 30 is connected to one end of the housing 27. The housing is adapted to be secured to the inner face of the projecting arm of the bracket 15 substantially in an inclined position, that is, 35 with the open end so that when the actuating bar is moved downwardly or away from the closed end 30 of the shade it will be disposed below the open end of the housing and when the actuating member is moved 40 toward and into engagement with the shade the open end of the sleeve will be disposed below the closed end of the housing.

The housing 27 is intended to receive a pawl 31, the diameter of the housing being 45 slightly greater than the diameter of the pawl so as to permit unobstructed sliding movement of the pawl within the housing. The end 32 of the pawl is reduced and is adapted to extend at times through the 50 open end of the housing. The opposite end of the pawl is intended to engage the closed end of the housing. The end 32 of the pawl is arranged to extend into one of the openings or recesses 25 of the collar 24 to prevent 55 rotation of the collar.

When the shade roller is in its inoperative position, the actuating member 14 is disposed in engagement with the outer face of the shade 8, or in other words, between 60 the shade and the window casing 5. When the actuating member is so positioned the open end of the housing is disposed below the closed end of the housing. At the same time the housing is also inclined with 65 respect to the brackets 15 thereby permit-

ting gravity to urge the pawl 31 into one of the openings 25 of the collar 24 to prevent rotation of the roller. To release the roller and permit winding or unwinding of the shade from the roller, a handle 33 is secured to the intermediate portion of the actuating member 14 and adapted to extend below the shade roller 16. This handle is grasped so as to move the actuating member away from the shade and downwardly so as 70 to swing the lower end of the pawl, or end portion 31, upwardly and permit gravity to urge the pawl toward the closed end 30 of the housing. This causes release of the roller, whereupon the spring of the roller 80 rotates the same to increase or decrease the length of the shade as desired. As soon as the handle 33 is released, the actuating member through the medium of the shade 8 and spring 17 is immediately swung upwardly, thereby permitting the pawl 31 to descend and enter one of the openings 25.

From the foregoing it will be readily seen that this invention provides novel controlling means which is automatic in its operation and which in view of its simplicity and novel arrangement will positively prevent accidental rotation of the shade rollers and at the same time eliminate the necessity of tilting or moving the roller in order to release the same with respect to its mountings. In addition to this the actuating member is disposed behind the shade and all that is necessary to permit rotation of the roller is to grasp the handle 33 and move the same in the direction desired.

What is claimed is:

1. Shade controlling means of the character described comprising a manually operable member, brackets carried by said member, a spring actuated shade roller having stub shafts projecting from the ends thereof, said shafts being mounted in said brackets, one of said shafts having a ratchet collar, said collar having a series of depressions, a housing carried by one of said brackets, and a gravity pawl slidable in said housing, said pawl being normally disposed in a substantially vertical position and adapted to enter one of the depressions of the collar, said pawl being adapted to leave said depression to release the roller upon movement of the bracket carrying the housing to a substantially horizontal position.

2. Shade controlling means of the character described comprising a manually operable member, brackets carried by said member, a spring actuated shade roller rotatably mounted on said brackets, a ratchet or collar carried by the roller, said collar having a series of depressions, a housing carried by one of said brackets, said housing being disposed obliquely of said bracket and having one end thereof open for the re-

ception of a gravity pawl, said pawl being freely mounted within the housing, one end of said pawl being adapted to slide into one of the depressions of the collar through the medium of gravity upon movement of the actuating member toward the shade. In testimony whereof I hereunto affix my

signature.

JOHN C. SPENCER.
